PRINTING PRESS FOR NEWSPAPER WORK

Maurice Eiseman, Washington, D. C.

Application October 9, 1930, Serial No. 487,606

19 Claims. (Cl. 270—5)

This invention relates to printing presses, and particularly to presses for printing newspapers and the like, and has for its object to provide for perforating the sheets of the newspapers along the lines of fold thereof for the purpose of enabling the reader thereof to effect a convenient refolding of the sheets back to back from an open position of the sheets, and vice versa.

It is a common practice, particularly on trains, street cars and the like, for the reader of a newspaper to unfold and open the sheets of the newspaper to a desired page, and then reversely fold the sheets back to back so as to bring a desired inner page into view, the newspaper being then in its original compact form. However, much difficulty is experienced in so opening and then reversely folding the sheets or pages, a considerable amount of close attention, experience and skill being required to open and reversely fold a newspaper into its original flat and compact condition. This is particularly true, where, as is usual, the newspaper has been folded across its middle transverse to the page fold lines of the several sheets of the newspaper, as the intersections of these angular disposed fold lines causes the large flimsy sheets of news print paper to buckle which prevents the quick and convenient refolding of the sheets back to back, and requires special and careful manipulation of the sheets along their fold lines to bring the newspaper into the desired reversely folded and compact form.

In view of the disadvantages above pointed out, it is the prime object of the present invention to provide the several sheets of a newspaper with perforations or weakened portions along the fold lines thereof which will enable the convenient unfolding and reverse folding of the pages in a simple and convenient manner and without danger of the sheets buckling along the fold line.

The perforating may be done at any of a large number of places on the printing press, and in the accompanying drawings I have illustrated means for perforating at different places in the press.

With these and other objects in view, the present invention consists in the combination and arrangement of parts as will be hereinafter more fully described, illustrated in the accompanying drawings and particularly pointed out in the appended claims, it of course being understood that changes in the form, proportion, size and minor details may be made, within the scope of the 55 claims, without departing from the spirit or sac-

rificing any of the advantages of the invention.

In the drawings:

Figure 1 is a fragmentary front elevation of a portion of a newspaper printing press showing a pair of formers for folding the paper and equipped with means for perforating the paper along the line of fold between sheets of the product of the printing press.

Figure 2 is an enlarged detail fragmentary sectional view taken on the line 2—2 of Figure 1.

Figure 3 is a view similar to Figure 1 showing another embodiment of the invention for perforating the paper at a different portion of the former.

Figure 4 is an enlarged detail fragmentary sectional view on the line 4—4 of Figure 3.

Fig. 5 is a front elevation of Fig. 6 showing the nipping rolls in section and equipped with perforating means.

Fig. 6 is a side elevation of a former for folding the so-called tabloid newspaper and equipped with means for perforating the same along the fold line.

Figure 7 is an enlarged detail fragmentary sectional view on the line 7—7 of Figure 6.

Figure 8 is a detail view illustrating a newspaper perforated in accordance with the present invention.

Figure 9 is a side elevation of a conventional printing roll such as is employed in the form of the invention illustrated in Figures 1 to 4 inclusive and showing the printing columns extended circumferentially of the roll.

Figure 10 is a side elevation of a conventional form of printing roll for use in printing the so-called tabloid sheets, such as shown in Figures 5 and 6 of the drawings, the printing columns extending longitudinally of the roll.

In Figures 1 and 2 of the drawings, 1 designates the usual former commonly employed on newspaper printing presses for folding the printed paper as it is fed to the former. The print paper is indicated at 2, and this print paper, which has been printed in the usual column formation in the newspaper, is severed longitudinally by the usual cutting means 3 to divide the paper into two longitudinal strips, each strip of course being a duplicate of the other. The paper of course is fed along by and between a feed or drag roller 4 and presser rolls 5 mounted upon a shaft 6, all of which is common and well known and constitutes no part of the present invention. It will of course be understood that the former, shown in Figures 1, 3, 5 and 6 is used in conjunc- 55

tion with any common or preferred form of printing mechanism such as will print page sections in columned and spaced newspaper formations on a web of paper, such columned formations being indicated on the paper 2 as shown in Figures 1, 3, 5 and 6, and therefore it has not been deemed necessary to show in the drawings any form of printing mechanism.

In carrying out the present invention, in the form exhibited in Figures 1 and 2 of the drawings, the shaft 6 is provided with a wheel or roller 7, which may be the usual presser roller commonly employed to press the paper against the drag roll 4 at this point, and this presser roller is provided with a series of blades 8 arranged to register with a series of seats or perforations 9 in the drag roller 4, whereby the paper will be perforated, as will be readily understood by reference to Figure 2 of the drawings, so as to produce a line of perforations 10 in the unprinted central longitudinal space or column of the paper and along which the paper is folded as it passes down along the former 1 between the usual forming rollers 11 and nipping rollers 12. It will of course be understood that after the web of paper has been folded and perforated and passes out from between the nipping rolls 12, it will subsequently be cut transversely into page sections in any common or well known manner, and therefore it has not been deemed necessary to illustrate any means for so cutting the web into sections.

It will of course be understood that several printed webs of paper are superimposed by the printing press and fed across the drag roller 4 and downwardly across the former 1 and therefore it will be further understood that all of these webs are perforated at the same time so as to produce the effect shown in Figure 8 of the drawings. This perforated line weakens the paper along the fold line and enables the convenient refolding of the newspaper by the reader thereof in the manner fully set forth in my co-pending application filed July 3, 1930, Serial No. 465,676, which has eventuated in Patent No. 2,011,572, issued August 20, 1935.

With the provision of perforations or weakened portions along the fold lines of the several sheets of the newspaper, it will be found that with the newspaper in its open condition, as in Fig. 8, and the opposite outer longitudinal edge portions of the newspaper held in the respective hands of the reader, the entire newspaper may be conveniently folded back to back merely by throwing the hands away from the body and inwardly towards one another until the sheets have been folded back to back.

Should the operation of the perforating wheel 7 produce any cuttings, it is desired to carry off such cuttings by permitting them to fall into the hollow drag roller 4 and to be drawn out of the ends thereof through suitable tubes 13 connected to a suitable source of suction.

The shape of the cutting blades 3 may be varied to produce actual perforations of different shapes, instead of mere slits, all of which will be understood by reference to my co-pending application hereinbefore referred to.

Instead of perforating the paper as it passes across the drag roller 4, it may be perforated at the place indicated in Figures 3 and 4 of the drawings, wherein 14 designates a shaft, suitably driven in any manner from some moving part of the printing press and provided with a presser wheel 15 bearing upon the unprinted longitudinal central portion of the paper 2 adjacent the lower

end of the former 1, this presser wheel being provided with suitable blades 16 to perforate the paper, the former 1 being provided with an opening 17 to accommodate each blade and permit the same to cut the paper. A suitable suction pipe 18 may be connected to the underside of the former at the opening 17 so as to carry off whatever cuttings may be produced by the rotating perforating member. The forming rolls 11 and the nipping rolls 12 of course are present as in Figure 1.

In Figures 5, 6 and 7, there has been shown means for perforating so-called tabloid newspapers, and in these figures there has been shown a former 1, a drag roller 4, a shaft 6 carrying presser rolls, or wheels, one of which has been shown at 5, a cutting device 3 to sever the longitudinal print paper into two newspapers, and another cutting device 19 on the shaft 6, for cutting paper into sheets of the tabloid paper. In the tabloid form of paper the columns of each sheet, instead of extending in the direction of the travel of the paper as in Figure 1 of the drawings, extend transversely of the direction of travel, as well indicated in Figures 5 and 6 of the drawings. The cutter 19 cuts the tabloid web so as to sever it along the line designated 20, and thus divide it into two webs, each of which passes downwardly at one side of the former as best shown in Figure 5, and between the usual forming rollers 11. The nipping rollers 21 are very much larger than the usual nipping rollers and one of them is provided with a longitudinal series of blades or perforating members 22, and the other nipping roller is provided with a series 35 of seats or perforations 23 to receive the blades, so that as the tabloid webs are fed downwardly by and between the nipping rolls 21, the tabloid webs will be perforated in parallelism with the printed columns and in the unprinted space, designated 24, along which the tabloid sheet is subsequently folded by any of the well known or preferred forms of folding means. Preferably the nipping roll which is provided with seats or perforating members 23, is hollow and is provided at both ends with suitable tubes 25 connected with a source of suction so as to carry off any cuttings which may be produced by the perforating means.

It will be understood that the cutter 19, in Figures 5 and 6 slits the web longitudinally and thereby divides it into two webs which are acted upon by the former 1 and the forming rollers 11 so as to bring the two web portions face to face as they pass between the nipping rollers 21, and thereafter the two webs are severed transversely to form page sections which are folded by any well known or preferred form of folding means along the unprinted portion 24 in which the perforations have been formed. Inasmuch as cutting and folding mechanisms which act upon the tabloid webs after they pass beyond the nipping rollers are common and well known, it has not been deemed necessary to illustrate such mechanism in the present drawings.

What is claimed is:

1. In a printing press for printing newspapers, the combination with a former, of means co-operating therewith for forming a line of perforations in a printed web of paper as it passes along the former and in such portions of the web as will subsequently constitute the fold lines of the finished newspaper product of the printing press.
2. In a press for printing newspapers, the com-

bination with the drag roller thereof, of means cooperating therewith for forming a line of perforations in the fold lines of the newspaper product of the printing press.

5 3. In a printing press for printing newspapers, the combination with a hollow drag roller having a circumferential series of perforations, a perforating roll having perforating blades disposed in cooperating relation with the perforations 10 in the drag roller and a suction conduit connected with the drag roller to carry off the cuttings therefrom.

4. In a printing press for printing newspapers, the combination with a former, of a rotatable 15 perforating member having an annular series of cutting blades in cooperative cutting relation with the former to perforate the printed webs along the line of fold thereof, the former being provided with an opening to successively receive 20 the cutting blades.

5. In a printing press for printing newspapers, the combination with a former, of a rotatable perforating member having an annular series of cutting blades in cooperative relation with the former to perforate the printed webs along the line of fold thereof, the former being provided with an opening to successively receive the cutting blades, and suction means associated with the opening in the former for carrying off cuttings. 25

6. In a printing press for printing newspapers, the combination with a former and means for cutting the paper longitudinally as it passes along the former, of means for perforating the paper 30 along the fold lines of the sheets and at right angles with the line of travel thereof.

7. In a printing press for printing newspapers, the combination with a former, of means for cutting the traveling paper along the line of its 40 travel, nipping rolls below the former for feeding the paper, one of the nipping rolls being provided with a longitudinal series of perforating blades, the other nipping roll having a series of openings receiving the respective perforating 45 blades.

8. The combination with a newspaper press having means for printing in parallel columns and in sheet formation on a web and means for folding the printed web along an unprinted portion 50 thereof between adjacent printed columns, of means for perforating the web along the line of fold, substantially as and for the purpose described.

9. The combination with a newspaper printing 55 press having means for printing in parallel columns and in sheet formation on a web, means for superimposing a plurality of printed webs and feeding them simultaneously, and means for simultaneously folding the superposed printed webs along unprinted portions thereof between adjacent printed columns, of means for simultaneously perforating the superimposed webs along the fold lines thereof, substantially as and for the purpose described.

65 10. The combination with a newspaper printing press having means for printing in parallel columns and in sheet formation on a web, and means for folding the printed web along an unprinted portion thereof between adjacent printed 70 columns, of means for weakening the web along the line of fold, substantially as and for the purpose described.

11. The combination with a newspaper printing press having means for printing in parallel 75 columns and in sheet formation on a web, means

for superimposing a plurality of printed webs and feeding them simultaneously, and means for simultaneously folding the superimposed printed webs along unprinted portions thereof between adjacent printed columns, of means for simultaneously weakening the superimposed webs along the fold lines thereof, substantially as and for the purpose described. 5

12. A newspaper printing press having means for printing in parallel columns and in sheet 10 formation on a web, a former, forming rollers in cooperative relation with the discharge end of the former, and means to weaken the printed web along the fold line portion thereof produced by the combined action of the former and the 15 former rollers, substantially as and for the purpose set forth.

13. In a newspaper printing press, means for continuously feeding a web of print paper, means for printing in parallel columns and in sheet 20 formation on the web, means for folding the printed web of print paper while it is being fed, and means for weakening the web of print paper while it is being fed and along the fold 25 line made by the folding means.

14. In a newspaper printing press, means for continuously feeding a web of print paper, means for printing in parallel columns and in sheet 30 formation on the web, means for folding the web of print paper while it is being fed, and means for weakening the web of print paper while it is being fed and preparatory to being folded and along the fold line to be made by the folding means.

15. A newspaper printing press having means 35 for printing page sections in columned newspaper formations on a web, means for severing printed page sections from the web, means for folding the web to provide fold lines dividing the sections into pages foldably connected along the 40 fold lines, and means for weakening the fold line of the web and thereby form a newspaper having weakened fold lines.

16. A newspaper printing press having means for printing page sections in columned and spaced 45 newspaper formations on a web, means for folding the printed web longitudinally thereof and along unprinted portions of the page sections, means for severing the printed and folded web transversely thereof and along unprinted portions to separate page sections from the web, and means for weakening the web fold line to form a newspaper having weakened fold lines.

17. A newspaper printing press having means for printing page sections in columned and 55 spaced newspaper formations on a web, means for severing the printed web longitudinally and continuously along unprinted portions thereof to divide the web into two webs, former means for bringing the two web sections face to face, and 60 means for weakening unprinted portions of the two webs transversely thereof and in unprinted portions thereof between printed page formations.

18. A newspaper printing press having means 65 for providing fold lines in the newspaper product of the printing press, and means for weakening the fold lines of the newspaper for the purpose set forth.

19. A newspaper printing press having means 70 for providing fold lines in the newspaper product of the printing press, and means for perforating the fold lines of the newspaper for the purpose set forth.
